United States Patent

Des. 241,509
Patented Sept. 21, 1976

241,509

DOOR KNOCKER OR SIMILAR ARTICLE

Douglas Hinsdale Worrall, Jr., 121 W. Chestnut Hill Ave.,
Philadelphia, Pa. 19118

Filed Aug. 18, 1975, Ser. No. 605,273

Term of patent 14 years

Int. Cl. D8—09

U.S. Cl. D8—177

Fig. 3

Fig. 1

Fig. 2

*Fig. 5**Fig. 4**Fig. 6*

FIG. 1 is a perspective view of a door knocker or similar article, showing my design,

FIG. 2 is a front elevation view thereof,

FIG. 3 is a top plan view thereof,

FIG. 4 is a left side elevation view thereof, the right side elevation being a mirror image thereof,

FIG. 5 is a rear elevation view thereof, and

FIG. 6 is a bottom view thereof.

I claim:

The ornamental design for a door knocker or similar article, substantially as shown and described.
